UNITED STATES PATENT OFFICE.

AUGUST ARENS, OF NEW BRITAIN, CONNECTICUT, ASSIGNOR TO P. & F. CORBIN, OF NEW BRITAIN, CONNECTICUT, A CORPORATION OF CONNECTICUT.

ROLL-BACK HUB FOR LOCKS.

No. 923,755.

Specification of Letters Patent.

Patented June 1, 1909.

Application filed September 8, 1908. Serial No. 451,979.

To all whom it may concern:

Be it known that I, AUGUST ARENS, a citizen of the United States, residing at New Britain, county of Hartford, State of Connecticut, have invented certain new and useful Improvements in Roll-Back Hubs for Locks, of which the following is a full, clear, and exact description.

My invention relates to improvements in locks and particularly to an improved roll-back construction.

In locks, the means commonly employed for operating the latch or bolt mechanism is what is termed a "roll-back", the general style of which is well known. Through this roll-back passes a knob or key spindle which, when manually turned, causes the roll-back to turn therewith. Suitable connecting devices leading from the roll-back to the bolt or latch cause said bolt or latch to be moved when the roll-back turns. Since a roll-back is ordinarily mounted so as to oscillate only within the lock case, the result is, if for any reason the lock should be applied to a door carelessly and so as to be out of a plane at right angles to the plane of the operating spindle, a cramping or binding of the spindle occurs which interferes with the proper action of the lock.

The object of my invention is to provide a construction which will overcome this objection to the ordinary roll-back.

In the drawings, Figure 1 is a side elevation of a roll-back constructed to embody my invention. Fig. 2 is a longitudinal section through the axis of the roll-back hub. Fig. 3 is a perspective view of a detail of construction detached. Fig. 4 is a perspective view of a modification of the detail shown in Fig. 3.

My improved roll-back comprises the main body 1 having the reduced bearing ends 2-2 and the roll-back arm or arms 3-3. Extending longitudinally through the body 1 and from end to end thereof is a passage to afford clearance for a spindle. The usual cross-sectional outline of a spindle is square and in the present case such is preferably the outline of the spindle passage in the body 1. At a suitable point (preferably about midway) within this passage is located one or more spindle bearing plates 4-4; these plates may be of any suitable shape externally; and each of them is provided with a passage approximately fitting the spindle designed to be

used, yet affording a slight play. The size of the passage through each plate 4 is somewhat less than the size of the spindle clearance passage through the body 1; the result is, when a spindle is passed through this roll-back, it has its main operative bearing within the washer 4, the larger passage through the hub permitting said spindle to be tilted very considerably (as indicated by the dotted lines in Fig. 2), without danger of cramping or binding the roll-back.

The plates 4-4 are preferably made of a relatively hard material such as iron or steel, while the roll-back may be made of such material as brass which is comparatively soft. By making the spindle bearing washers 4-4 of a relatively hard material, great durability is afforded. The metal of the roll-back is preferably cast around the spindle bearing plates 4-4, this method of construction being found to be very satisfactory and affording a firm and positive locking of the plates in place, for, as the surrounding metal cools, it will shrink upon said plates and thereby guarantee a permanent connection. While a single plate 4, of the proper thickness, may be employed, greater economies are attained by employing a plurality of comparatively thin plates of corresponding size and shape, for, by such provision, said plates may be very economically produced. By placing two or more of these plates side by side a sufficiently broad spindle bearing may be provided to prevent wear upon the spindle, at the same time permitting said spindle to tilt in any direction to a sufficient degree to compensate for faulty application of the lock.

In Fig. 4 I have shown a spindle bearing plate 4^a, in which the outer edge is angular instead of round, as shown in Fig. 3. This serves to better anchor the member 4^a in place.

What I claim is:

1. A roll-back for locks comprising a main body, having bearing ends and having a spindle clearance passage therethrough extending from one end to the other, a separate perforated spindle bearing plate rigidly mounted within said body and arranged to embrace a spindle and arranged transversely of the spindle clearance passage, the inner edge of the said spindle bearing plate projecting into and reducing the diameter of the spindle clearance passage.

2. In a roll-back for locks, a main body | having a spindle clearance passage extending therethrough from one end to the other, a | separate spindle bearing plate embedded | 5 within the material of the main body and ar- | ranged transversely of the clearance passage | therethrough, and at a point intermediate | the ends of the same, and a passage through | said bearing plate adapted to receive a spin- | 10 dle.
3. In a roll-back for locks, a main body | having a spindle clearance passage extending therethrough, a perforated spindle bearing | plate arranged and embedded within the ma- | 15 terial of the said body at a point intermedia- | te the length of said passage, and arranged | to reduce the diameter of the passage at such | intermediate point through the roll-back and | to afford a bearing wall for the spindle.
4. In a roll-back for locks, a main body | having a spindle clearance passage extending therethrough, a spindle bearing plate ar- | 20
- | ranged therein, said plate having a rectangu- | lar passage and being embedded partially | within the material of the said body, a por- | 25 tion of said spindle bearing plate reducing | the size of the passage through the roll-back | to afford a bearing wall for the spindle, said | plate being located intermediate the ends of | the roll-back.
5. In a roll-back for locks, a main body | having a spindle clearance passage extending therethrough, perforated spindle bearing | plates arranged side by side and embedded | 30 within the material of said body at a point | intermediate the length of said passage, said | plates reducing the diameter of said passage | at such intermediate point to afford a bear- | ing wall for the spindle.

AUGUST ARENS.
